LIGHTING FIXTURE

Abraham Lazerson, Chicago, Ill.

Application July 24, 1936, Serial No. 92,328

7 Claims. (Cl. 240—78)

My invention relates to a lighting fixture and has particular reference to a lighting fixture of the indirect variety.

One of the objects of the invention is the provision of a fixture having means whereby the light bulb can be properly adjusted in a vertical direction with respect to the reflecting surfaces, thereby securing a maximum amount of efficiency from the light bulb.

Another and further object of my invention is the provision of a lighting fixture in which provision is made for the easy removal, for cleaning purposes and the like, of the reflector used in connection with the lighting fixture and for relamping or placing new light bulbs in the fixture when it becomes necessary to replace the light bulb due to breakage, burning out, or the like.

Another and further object of my invention is the provision of a light fixture in which the dark or shadow spot immediately under the fixture is eliminated and an even distribution of light rays is made throughout the room.

Another and further object of my invention is the provision of a light fixture of an indirect variety and in which the light rays are so distributed that shadows from the light fixture are eliminated and an even distribution of light rays is secured in and about the lighting fixture.

These and other objects of my invention will be more fully and better understood by reference to the accompanying sheets of drawings, and in which—

Figure 1 is a perspective view of my improved light fixture;

Figure 2 is a view partially in elevation and partially in section of the fixture on line 2—2 of Figure 3;

Figure 3 is a plan sectional view on line 3—3 of Figure 2;

Figure 4 is a detail sectional view showing the socket and stem connection for the light fixture;

Figure 5 is a top view of the central reflector;

Figure 6 is a top view of the ring to which the reflector shown in Figure 5 is attached;

Figure 7 is a detail sectional view showing the edge contours of the ring and central reflector shown in Figures 5 and 6; and

Figure 8 is a detail vertical sectional view on line 8—8 of Figure 3.

Referring now specifically to the drawings, and in which like reference characters refer to like parts throughout, a central flat circular reflector plate 10 is shown, this plate being preferably made of metal having a highly polished reflecting surface, or is made of glass or any other suit-

able material. The reflector plate 10 has a central opening therein and a plurality of brackets 11, 11 extending radially from said central opening, which brackets are upturned at their outer ends and have a metal ring 12 secured thereto. A flange 13 extends around the ring 12 at its lower edge and projects inwardly a short distance, the ring 12 being spaced apart from the outer periphery of the plate 10 to allow light rays to pass therearound, as shown particularly in Figure 2 10 and as will be more fully described hereinafter.

Mounted against the under side of the plate 10 is a glass ring 14, the inner edge of which is in substantial register with the edge of the plate 10 around the opening in the center thereof, this glass preferably being translucent and adapted to receive rays of light along its inner edge which are distributed throughout its surface and directed downward, thereby providing light on the under side of the fixture, and is known in the trade 20 generally as an edge glow glass. The glass member is held in position by means of a ring 15 which has an annular portion 16 which engages the under side of the glass ring 14 for a short distance adjacent its inner edge, a vertical wall 17, 25 a channel portion 18 extending parallel with the annular portion 16 but in stepped vertical relation therewith, and with a downwardly extending annular flange portion 19 extending around the inner edge of the ring 15. Straps 20, 20 are provided which are secured to the plate 10 by means of rivets 21, 21 and which extend inwardly over the channel 18 of the ring 15, the ring 15 being secured to the straps 20, 20 by means of bolts 21a, 21a, with spacers 22, 22 being fitted over the bolts 35 21a, 21a between the plate 15 and the straps 20, 20, the bolts 21a, 21a being threaded into the straps 20, 20. The vertical wall portion 17 is approximately one-half as high as the glass ring 14 is thick, so that at least one half the edge of 40 the glass ring 15 is exposed to receive rays of light from the light bulb. The channel portion 18 has struckup sections 23, 23 adjacent which are slots 24, 24 for the reception of the fastening means for a reflector hereinafter described.

A reflector 25 of bowl-like form is provided having a channel portion 26 extending therearound, the reflector preferably being made of metal with a highly polished surface. A flange 27 is provided on the reflector 25, this flange being 50 approximately the same height as the annular channel portion 18 on the ring 15, with a downwardly extending wall portion 28 being provided, and a flange 29 of the channel portion 26 being provided, this flange 29 and the wall 28 forming 55

the sides of the channel section 26, and which is interfitted into the channel section 18 of the ring 15. Spring clips 30, 30 are provided which are secured to the portion 26 by means of rivets 5 31, 31 or other appropriate fastening means, and have tongues 32, 32 projecting therefrom which are received into the slots 24, 24 and fit under the struckup portions 23, 23 in the channel section 18, the clips having upturned ends to be received 10 into the slots 24 and are slightly curved so that as the reflector 25 is placed in position the clips are placed under tension to hold them securely in position and also render them tight and imper- 15

5. The reflector 25 is placed in position by being fitted against the channel 18 of the ring member 15, and the reflector turned in a counterclockwise direction until the clips are received in the 20 slots 24. A further slight turn tightens the reflector into position under the lamp, in assembled relation. When it is desired to remove the reflector for relamping the fixture, the reflector is twisted in a clockwise direction, thereby releasing the clips 30 and allowing the ready removal of the reflector so that access may be had to the lamp.

25. A suspension means for securing the light to a ceiling includes a hollow stem 33, to the upper end of which a canopy 34 is provided, with the usual swivel joint 35 and the nipple 36. Suitable lead wires 37 and 38 are provided which pass through the nipple 36 and stem 33 downward to a socket 39 which has the lamp 40 mounted therein in the usual manner. At the lower end 30 of the stem 33 a suspension member is provided having a socket portion 41 and a flange portion 42, with screws 43 being provided which extend through the socket portion 41 by means of which the suspension member is secured to the stem 33. 35. The flange 42 has a plurality of holes 44, 44 therein through which threaded studs 45, 45 extend, these studs having nuts 46, 46 thereon. The studs are threaded into the upper edge of the socket 39 and locked in place by means of lock nuts 47, 47, with the nuts 46 being loosely positioned upon the studs 45 and through which a vertical adjustment of the socket 39 is made. The socket 39 with the lamp therein is suspended by means of the studs 45 and nuts 46.

50. A husk 48 is provided, to the lower end of which a plurality of braces 49, 49 are secured in any approved manner. The ends of these braces are turned at right angles to the body thereof and are secured to the inner edge of the plate 10 by the rivets 21, 21 which pass through the plate 10 and the straps 20, 20, thus securing this portion of the fixture together in permanently fixed relation. The upper edge of the husk 48 has an inwardly turned flanged portion 50 which engages over the flange portion 42 of the suspension member, and which in turn supports the entire lower portion of the lighting fixture. A slidingly mounted cap 51 is provided which is fitted over the upper end of the husk 48 and is supported by an annular flange 52 extending around the upper end of the husk 48. When it is desired to adjust the socket 39 and lamp 40 in the proper position, the cap 51 is lifted, the nuts 46 turned on the studs 45, and the socket, including the lamp, 65 may be raised and lowered as desired.

70. In operation it will be understood that the device is suspended from a ceiling in any suitable manner, and is placed in position in assembled relation. When it is desired to renew the lamp it 75 is only necessary to remove the reflector 25 by

turning it in a counterclockwise direction, when the lamp 40 can be easily removed from the socket, being in threaded engagement therewith in the usual manner, and replaced with a new lamp. When this replacement is made, the lamps, which even with one manufacturer vary in length with relation to the neck portion thereof, may be placed in proper adjusted position with respect to the reflector as heretofore described, by moving the cap 51 upward along the stem and adjusting the height of the socket by means of the nuts 46 on the studs 45 to secure the best position of the lighting bulb to obtain maximum results. The lamp 40 must be fairly low in the reflector in order to obtain the maximum lighting effects from it and yet not too close to secure the proper reflection and transmission of light rays from the reflector.

When the device is in assembled position, the light rays pass upward and outward from the lamp 40, some of the rays striking against the metal ring 12 at the outer edge of the plate 10 and reflecting downward around the edge of the plate 10 underneath the fixture. Other rays striking against the ring 12 pass to the under side of the plate 10, while others are reflected upward by means of the flange 13 directly against the under side of the plate 10. Rays passing through the edge of the glass ring 14 are distributed in and about the under side of the reflector 25 thereby lighting the entire space underneath the fixture in such manner that a shadow which might be produced in the room by reason of the reflector plate 10 is entirely eliminated. The rays of light are distributed so thoroughly 30 in a plurality of directions that not only are they evenly distributed throughout the room for purposes of illumination, but the fixture itself is so completely lighted that all dark spots in and adjacent the fixture are eliminated. In addition, the device possesses the factors of adjustment as far as the lamp is concerned, as heretofore described.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. A lighting fixture comprising, in combination, a reflector plate having a central opening therein, a reflector ring around the outer edge of said plate having an inwardly turned flange around the lower edge thereof, the reflector ring being spaced from the outer edge of said plate, brackets connecting the plate and reflector ring, the plane of the plate being between the upper and lower edges of the reflector ring, a removable reflector secured to said plate and closing the central opening therein, means whereby the said plate is suspended, a lamp socket carried by said suspension means, and a lamp in said socket and extending into said central opening.

2. A lighting fixture comprising, in combination, a plate having a central opening therein, a reflector ring around the outer periphery of the said plate and spaced therefrom, suspension means secured to the said plate, a translucent ring on the said plate encircling the said opening therein, means whereby the said ring is retained against the said plate, a bowl-shaped reflector secured to said plate, and a lamp mount-

ed in said suspension means and extending into said central opening and said reflector.

3. A lighting fixture comprising, in combination, a plate having a central opening therein, a reflector ring around the outer periphery of the said plate and spaced therefrom, suspension means secured to the said plate, a translucent ring on the said plate encircling the said opening therein, a metallic ring one edge of which overlaps the said translucent ring, a bowl-shaped reflector secured to said metallic ring, and a lamp mounted in said suspension means and extending into said central opening and said reflector.

4. A lighting fixture comprising, in combination, a plate having a central opening therein, a reflector ring around the outer periphery of the said plate and spaced therefrom, suspension means secured to the said plate, a translucent ring on the said plate encircling the said opening therein, the inner edges of the opening in said plate and the ring being in register with each other, a metallic ring one edge of which overlaps the said translucent ring, a bowl-shaped reflector secured to said metallic ring, and a lamp mounted in said suspension means and extending into said central opening and said reflector.

5. A lighting fixture comprising, in combination, a stem, a plate having a central opening therein supported by said stem, a reflector ring supported by said plate and spaced therefrom extending around the outer edge thereof, a translucent ring surrounding the opening in said plate, a metallic ring having a channel section overlapping the said translucent member and secured 35 to said plate, having fastening means thereon, a reflector fitted into said opening in said plate, fastening means on the outer periphery thereof adapted to coact with the fastening means on

said metallic ring, a socket, and a lamp in said socket extending into said reflector.

6. A lighting fixture comprising, in combination, a stem, a plate having a central opening therein supported by said stem, a reflector ring 5 extending around the outer periphery of said plate and spaced therefrom, a translucent ring surrounding the opening in said plate placed in face to face relation with said plate, a metallic ring supporting said translucent ring having a 10 channel section extending inwardly from the edge of said translucent member, a bowl-shaped reflector having a channel section therearound fitted into the opening in the plate, a lamp socket, a lamp extending into the bowl reflector and 15 opening in the plate, and interengaging fastening means on the channel sections of the reflector and the metallic ring.

7. A lighting fixture comprising, in combination, a stem, a plate having a central opening 20 therein supported by said stem, a reflector ring extending around the outer periphery of said plate and spaced therefrom, a translucent ring surrounding the opening in said plate placed in face to face relation with said plate, a metallic 25 ring supporting said translucent ring having a channel section extending inwardly from the edge of said translucent member, openings in said channel section, a bowl-shaped reflector having a channel section therearound fitted into 30 the opening in the plate, clips on the channel section of said reflector having tongues thereon adapted to be received in the openings in the channel section of said metallic member, a lamp socket, and a lamp extending into the bowl reflector and opening in the plate. 35

ABRAHAM LAZERSON.
